Primary Examiner — George A Bugg*Assistant Examiner* — Cole Sanders Holman(74) *Attorney, Agent, or Firm* — Jose Cherson Weissbrot(57) **CLAIM**

The ornamental design for a multifunctional emergency radio with wrist strap, as shown and described.

DESCRIPTION

FIG. 1 is a perspective view of a multifunctional emergency radio with wrist strap, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The evenly spaced broken lines in the drawings depict portions of the multifunctional emergency radio with wrist strap that form no part of the claimed design. The unshaded surfaces enclosed by broken line features form no part of the claimed design.

1 Claim, 7 Drawing Sheets(56)
